UNITED STATES PATENT OFFICE.

GRANT D. BRADSHAW, OF BEAVER, PENNSYLVANIA.

GAS BURNER.

Application filed September 8, 1921, Serial No. 499,282.

To all whom it may concern:

Be it known that I, GRANT D. BRADSHAW, a citizen of the United States, and resident of Beaver, in the county of Beaver and State 5 of Pennsylvania, have invented a new and useful Improvement in Gas Burners, and I do hereby declare the following to be a full, clear, and exact description thereof.

My invention relates to gas burners.

10 In Letters Patent of the United States No. 1,149,622, granted to me August 10, 1915, there is set forth and claimed a gas burner which comprises generally stated a converging inlet passage, a diverging outlet passage, 15 air openings in and adjacent to the smaller cross section of said burner, and valves for controlling the size of said air openings, so that as the gas enters the larger end of the converging passage of the burner its velocity 20 is increased as it passes therethrough, and as it passes the air openings, by reason of the fact that the static head at the air openings is less than zero or a partial vacuum, the air is drawn through the air openings, 25 mixed with the gas, and is discharged through the divergent outlet passage in condition for proper combustion.

In that invention the body of the gas- 30 burner was made in one piece, so that there was no way of varying the throat area be- 35 tween the converging or diverging passages whereby such area could be made either larger or smaller, so as to enable a given quantity of gas per minute to be passed 40 through the throat at several different ve- 45 locities in order to vary the intimacy of mix- 50 ture, and in this way to vary the length of the flame in the combustion chamber.

The object of the present invention is to 40 improve the above, as well as other, burners in this respect and to these ends my inven- 45 tion comprises the novel features hereinafter set forth and claimed.

In the accompanying drawing Fig. 1 is a 45 vertical longitudinal sectional elevation of my improved burner in one of its forms; Fig. 2 is a like view showing the converging and diverging passages increased in size by the insertion of a thicker liner; and Fig. 3 50 is a front view of my improved burner.

While I have illustrated my invention in connection with a burner such as covered by said Patent No. 1,149,622, I do not wish to limit it in any sense to a burner of that construction.

My improved burner is made up of two preferably symmetrical halves 2 and 3, each half being provided with registering flanges 4 through which pass the bolts 5 for securing the halves together. The internal construction of the burner illustrated is the same as in said Letters Patent, there being the converging inlet passage 6 and the diverging outlet passage 7 with the air inlets 8 at or near the junction or throat of the converging and diverging passages. These air inlets are controlled by suitable dampers 9.

Where it is desired to reduce the throat area and the size of the passages, the bolts 5 are removed and a certain amount of metal 70 is removed from the flanges 4 by planing or otherwise, whereupon the halves are again secured together.

The rear plate of the burner has the slots 12 formed therein to receive the bolts 13 75 which connect the inlet pipe 14 to the burner. The discharge opening 15 of the supply pipe 14 should preferably be equal to or larger than the inlet of the converging passage 6 80 whatever the size of the liner employed.

The bolts 5 which connect the halves of the burner may be removed and a liner 17 of proper thickness is introduced between the flanges 4 and the bolts are then adjusted and secured in place as shown in Fig. 2. In this way the size of the converging passages 6 and 7 are increased and likewise the throat area connecting such passages at the point where the air is admitted.

By my invention I provide a simple and efficient means by which the burner may be quickly changed to enable a given quantity of gas per minute to be passed through the throat at several different velocities in order to vary the intimacy of mixture, and in this way vary the length of the flame in the combustion chamber, so that the scope of the burner is greatly increased, and instead of having to install new burners under conditions where greater or less velocity is de- 100 sired, the same burner may be made to do.

What I claim is:

1. A gas burner of the Venturi type di- 105 vided longitudinally into sections, securing means for holding said parts together, a liner inserted between said sections, a plate at the rear of said burner having slots formed therein, a supply pipe having flanges, and bolts passing through said flanges and slots. 110

2. A gas burner of the Venturi type divided longitudinally, and means for separating the divided venturi for adjusting the throat area of said burner while maintaining the angular relation of the walls of said burner substantially fixed relative to each other.
3. A gas burner of the Venturi type, having two parts, and means for relatively 10 adjusting the parts of the venturi to adjust the throat area of said burner while maintaining the angular relation of the walls of said burner substantially fixed relative to the longitudinal axis of the burner
- 15 4. A gas burner of the Venturi type divided longitudinally to form separable sections, securing means for holding said sections together, a removable liner inserted between said sections, a slotted projection 20 on each of said sections, a flanged supply pipe cooperating with said projections, and securing means maintaining said supply pipe in cooperative relation to said projections and permitting relative adjustment 25 therebetween.
5. In a gas burner, a mixing venturi, means for feeding a combustion supporting ingredient to said venturi under pressure, said venturi having a laterally extending opening terminating adjacent the 30 region of reduced pressure therein for the passage of a second combustion supporting ingredient in accordance with the pressure conditions in said venturi, and means whereby the inlet and outlet areas of said venturi 35 may be simultaneously varied for varying

the ratio of both the inlet and outlet of said venturi to the throat.

6. A gas burner of the Venturi type comprising a mixing chamber having inlets 40 leading to a point adjacent the region of minimum pressure therein, said chamber being divided longitudinally to form separable sections, and means for detachably securing said sections together. 45

7. A gas burner of the Venturi type comprising a mixing chamber having inlets leading to a point adjacent the region of minimum pressure therein, said chamber being divided longitudinally to form separable sections, and means for detachably securing said sections together, each of said sections having projecting flanges for the reception of said securing means. 50

8. A gas burner of the Venturi type comprising a mixing chamber having inlets leading to a point adjacent the region of maximum depression therein, said chamber being divided longitudinally to form separable sections, means for detachably securing said sections together, each of said sections having projecting flanges for the reception of said securing means, and spacing means detachably secured in position between said flanges. 55

In testimony whereof I, the said GRANT D. BRADSHAW, have hereunto set my hand.

GRANT D. BRADSHAW.
